(57) **CLAIM**

The ornamental design of a grain auger housing having an askewed discharge outlet attachment, as shown and described.

DESCRIPTION

FIG. 1 is a perspective view of a grain auger housing having an askewed discharge outlet attachment, showing my new design;

FIG. 2 is a front perspective view thereof;

FIG. 3 is a rear perspective view thereof;

FIG. 4 is a top and front perspective view thereof; and,

FIG. 5 is a bottom and rear perspective view thereof.

1 Claim, 3 Drawing Sheets

FIG. 1

FIG. 2

FIG. 3**FIG. 4****FIG. 5**
